LUBRICATING DEVICE

Filed Oct. 31, 1924

Inventor:

By Walter H. Cotton
Gillson, Mann & Cox
Atty's.

UNITED STATES PATENT OFFICE

WALTER H. COTTON, OF CHICAGO, ILLINOIS

LUBRICATING DEVICE

Application filed October 31, 1924. Serial No. 747,030.

The invention relates to lubricators, and particularly to those of the cup type for oiling working surfaces exposed to steam pressure.

5 One of the objects of the invention is to provide automatic means for controlling the flow of lubricant from the container. A further object is to provide means for augmenting radiation of heat from the container and 10 furthermore, to prevent the wasteful flow of lubricant when steam is shut off the chamber to which the device is applied.

Other and further objects and advantages of the invention will appear from the following description taken in connection with the 15 accompanying drawings, in which

Fig. 1 is a central vertical section showing the invention;

Fig. 2 is a top or plan view; and

20 Fig. 3 is a vertical section showing a modification of a detail.

The device consists of a body portion 10 provided at its lower end with a securing nipple 11 and an angular portion 12 for the 25 engagement of a wrench for attaching the nipple to its support in the usual manner. A dome shaped cap 16 removably secured to the body portion 10 forms a closure for the chamber or lubricant container 17.

30 A tube 13 extending axially through the container 17 is provided with a spring closed valve 14. The valve is held in operative position and is enclosed in a valve chamber formed by the cap 15 which is threaded to the tube. A hole 26 in cap 15 completes a passage from the tube 13 to the chamber 17.

The body portion 10 is preferably provided with radiating ribs 18 for cooling said container. The body portion may, if desired, be 35 provided with a pet-cock 19 secured to a passage leading from the bottom of chamber 17 for removing the water of condensation as occasion may require.

The device is shown secured to a steam 40 chest 20 in which numeral 21 designates a steam passage which communicates with tube 13.

The operation of the device is as follows: 45 The chamber 17 being filled with lubricant 50 such as grease, and cap 16 replaced, the de-

vice is ready for service. Steam entering the passage 21 will pass up tube 13 raising valve 14 and continue through passage 26 into chamber 17. If the container is filled with grease it will immediately melt and become a liquid. When the pressure in chamber 17 equalizes the pressure in the tube the valve will drop and close the passage. Condensation now takes place in chamber 17, the lubricant being lighter than the water of condensation will float and be forced into the valve chamber. The recession of temperature and pressure in chamber 17 will again cause the lifting of the valve and a small quantity of lubricant spreading out as a film on the walls of the tube will pass down the tube at each impulse. Should steam be shut off from the chest 20 the valve 14 will cease its impulse and stay closed, preventing further flow of lubricant until the steam is let on again.

In the modification shown in Fig. 3 the tube 130 is threaded to the body portion 10 and a ball valve 140 is seated at the throat of the tube. A chamber 22 near the top of the tube is filled with fibrous material such as cotton wick which may be compressed to any desirable degree by a screw 23 having a small passage 24. Tube 130 also is contracted at 25 below chamber 22.

The fibrous material forms a further impediment to the passage of matter through tube 13 which will result in slower but somewhat similar operation of valve 140 to that shown in Fig. 1.

What I claim as my invention and desire to secure by Letters Patent, is:—

1. In a lubricating device, in combination, a lubricant container, a steam chamber, a passage between the container and steam chamber, said passage comprising a tube extending upwardly within said container, a spring pressed valve closing the upper end of said passage when the pressure within said container and chamber are equalized, said valve being adapted to be moved by the steam pressure to open said passage when the pressure in said chamber exceeds that in said container, and a cap within said container threaded on the upper end of said tube for

enclosing said valve and for positioning the same on the upper end of said passage.

2. A lubricating device comprising a container provided with a threaded nipple extending outwardly therefrom and a tube extending upwardly therein, said tube and nipple being provided with a bore, a spring pressed valve for closing the upper end of said bore, a cap for enclosing said valve, said cap having an aperture through its side wall, a closure for said container for enclosing said tube, cap and valve, a pet cock in communication with the lower portion of said container, and heat radiating ribs on the exterior of said container.

15 In testimony whereof I affix my signature.
WALTER H. COTTON.
